ELECTROMAGNETIC FOCUSING COIL

Denis Victor Ridgeway, London, England, assignor to Baird Television Limited, London, England, a British company

Application June 27, 1939, Serial No. 281,372
In Great Britain January 13, 1939

3 Claims. (Cl. 250—161)

This invention relates to improvements in electromagnetic focus coils for use with electron discharge devices and is especially concerned with an improved method of screening and mounting 5 a focusing coil such as is used for focusing the electron beam in a cathode ray tube.

It has previously been proposed to screen a short-multi-layer focus coil by placing it in an iron shielding member comprising two annular 10 end pieces and a cylindrical member connecting them. It is found that when the focus coil is placed closely adjacent to an unsymmetrical electromagnetic deflecting yoke, distortion of the focusing field extending outside the screening member is produced owing to the asymmetry of the said yoke and it is an object of the present 15 invention to provide a focus coil in which the spread of the focusing field may be substantially reduced.

20 According to the present invention there is provided a focus coil for use with an electron discharge device comprising an electromagnetic coil enclosed by a screening member or members so arranged that at least two annular shielding 25 members spaced from each other by a distance substantially greater than their thickness are interposed immediately adjacent to each end of said coil.

A screening member according to the present 30 invention may conveniently be constructed by enclosing the coil in a screening member composed of a number of pressings of ferro-magnetic material, the said pressings being such that they have an annular end portion, a cylindrical 35 portion and a flange attached to the end of said cylindrical portion other than that to which said annular portion is attached. Pairs of such pressings may be assembled together to form a screening member according to the present invention.

40 In order that the present invention may be more particularly described reference is now made to the accompanying diagrammatic drawing of which:

Figure 1 is a cross-section through a focus coil 45 and screening member according to the present invention, while

Figure 2 illustrates a convenient method of mounting a screen focus coil according to the invention.

50 In Figure 1 a short multi-layer focus coil 1 is enclosed in a screening member built up of pairs 2, 3 and 4, 5 of pressings of the type described above. The whole screening assembly may be fastened together by suitable bolts or 55 rivets passed through holes 6 to form a single structural unit. Obviously another pair of more

deeply dished pressings may be added if still further screening is desired.

A convenient method of mounting a focus coil as illustrated in Figure 1 is illustrated in Figure 2 in which 7 is a complete focus coil and screening 5 assembly of the kind shown in Figure 1, while 8 and 9 are brackets in each of which is an aperture having partially circular edges 10 which bear upon the flange 11 of the coil 7 so as to constitute in effect a spherical mounting for the latter. Obviously this arrangement may be modified without departing from the feature that a comparatively thin edged circular disc to which the focus coil is attached is retained in position between 10 two members having apertures therein, the edges 15 of the apertures upon which the said disc bears being formed as circular arcs.

I claim:

1. Focusing means for use with an electron discharge device comprising an electromagnetic 20 coil and ferromagnetic shielding means surrounding said coil, said shielding means comprising a plurality of pairs of members, each of said members comprising a cylindrical portion, an annular portion extending inwardly from one 25 end of said cylindrical portion and a flange extending outwardly from the other end of said cylindrical portion, said members being assembled with their flanges abutting and the lengths of the said cylindrical portions varying from one 30 pair of members to another so that when the said flanges are placed in contact a space remains between the annular portions of one pair and those of the next larger pair.

2. Focusing means for use with an electron 35 discharge device and ferromagnetic shielding means surrounding said coil, said shielding means comprising two pairs of members, each of said members comprising a cylindrical portion, having an external flange at one end and an internal flange at the other end, one of said pairs of members being of such size as to fit closely 40 round said coil with the said external flanges in contact and the other of said pairs of members being arranged to fit over said first pair so that 45 when the external flanges of said second pair abut the external flanges of said first pair, a space remains between the internal flanges of said first and second pairs.

3. The combination with focusing means according to claim 1 of supporting means comprising two members each having an aperture with two arcuate edges, said arcuate edges gripping the flanges on said focusing means.
